ELECTRIC SWITCH

**Tomun Finizie, Bridgeport, Conn., assignor to
Edmond J. Finizie, Bridgeport, Conn.**

Application October 28, 1948, Serial No. 56,929

15 Claims. (Cl. 200—67)

1

This invention relates to electric switches, and more particularly to snap-action switches of the type in which a swinging contact member is employed cooperating with a stationary contact member.

An object of the invention is to improve and simplify switches of this type.

Another object is to provide an improved organization of switch elements.

Another object is to provide a simple and inexpensive structure which can be easily assembled and disassembled.

Another object is to provide a switch in which the number of screws or like fastening elements in the assembly is reduced to a minimum.

Another object is to provide a switch in which the snap action is of increased effectiveness.

In the accompanying drawings:

Fig. 1 is a top plan view of a switch embodying the invention, showing the same in the "off" position;

Fig. 2 is a front elevation of the switch shown in Fig. 1;

Fig. 3 is a section on line 3—3 of Fig. 1, on a larger scale;

Fig. 4 is a section on line 4—4 of Fig. 3, on a smaller scale;

Fig. 5 is a section on line 5—5 of Fig. 3;

Fig. 6 is a section on line 6—6 of Fig. 3;

Fig. 7 is a detail elevation of the swinging leaf;

Fig. 8 is a section on line 8—8 of Fig. 7;

Fig. 8A is a detail on a larger scale of a portion of the leaf;

Fig. 9 is a longitudinal section of a switch of modified form, showing it in the "on" position;

Fig. 10 is a view similar to Fig. 9, showing the "off" position, a portion of the structure being shown in elevation and a portion of the actuating member being broken away;

Fig. 11 is a detail perspective view of the leaf member employed in this form;

Fig. 12 is a section on line 12—12 of Fig. 11;

Fig. 13 is a top plan view of the switch, showing it in the position of Fig. 9, certain parts being broken away;

Fig. 13A is a sectional view, partly in elevation, showing a further modified form; and

Fig. 14 is a section on line 14—14 of Fig. 13.

In the form illustrated in Figs. 1 to 8A, inclusive, the switch is characterized by a frame composed in part of an upper block of insulating material and a lower metallic member, the insulation block being cut away intermediate of its ends to provide operating space for a leaf piv-

oted at its lower end to the metallic part of the frame and adapted to swing in a vertical plane lengthwise of the frame toward and away from contact members fixed in the cut-away portion 5 of the insulation block. The upper part of the metallic portion of the frame is cut away to provide an aperture in communication with the cut-away part of the block. Located at the lower part of the frame is an actuating element having a swinging motion to actuate the leaf through a coil spring, the upper end of the spring having a hook hooking into an aperture in the leaf, and the lower end of the spring being suitably connected to the actuating element. This actuating element in the form under discussion is formed as a plate suspended by the leaf-actuating spring, the spring being under tension and the actuating element being held in position by knife-edge pivoting spacing members interposed

10 between it and the upper part of the metallic portion of the frame. In this particular case, actuation of the leaf-actuating element is effected by extending one of the last-named members upwardly through the frame so that it is accessible for manual manipulation. The fixed contact members located in the cut-away portion of the insulation block, as above mentioned, are carried by the inner ends of conductor strips extending lengthwise along the top of the frame, and provided adjacent one end of the frame with suitable terminals for leading-in wires.

In the drawings, the frame as a whole is indicated at 20, the insulation block portion being indicated at 21 and the metallic portion at 22. 35 The swinging contact leaf is generally indicated at 23, the cut-away portion of the insulation block at 24, the cut-away portion of the metallic portion 22 of the frame at 25, the helical leaf-actuating spring at 26, the hooked upper end portion of this spring at 27, the lower actuating plate at 28, and the knife-edge spacing members at 29 and 30, respectively. The member 30 is provided with the upward extension 31 for manual manipulating purposes, said extension operating in a cut-away portion 32 of the frame. One of the fixed contacts cooperating with the swinging leaf is indicated at 33, the same being attached to a conductor strip 34, and the conductor strip 34 being equipped with a terminal screw 35. The other fixed contact 36 is similar, and is provided with a conductor strip 37 and a terminal screw 38.

The cut-away portion 24 extends transversely of the insulation block intermediate of the ends of the latter, and in this particular case the fixed

contacts 33 and 36 are located within this cut-away portion at the right-hand side of the latter (Figs. 1 and 3). The conductor strips 34 and 37 are located in grooves provided in the insulation block. The left-hand ends of the strips 34 and 37 are turned down to enter the cut-away portion 24 (Figs. 1 and 3), and the right-hand ends of the strips 34 and 37 are turned down within cut-away portions at the right-hand end of the block, and the turned-down portions provided with threaded sockets to receive the screws 35 and 38.

The metallic or conductive portion 22 of the frame is in the form of an inverted U, the connecting portion of which is uppermost and secured to the insulation block by means such as the screws 39.

The contact leaf 23 has a metallic body 40. This is a rectangular member extending along the cut-away portion 24 having at the lower middle part a hole or aperture 41^a in which the hook 27 of spring 26 is engaged. At the upper middle part the metallic member 40 has extended through it transversely a rivet 41 which holds in place a metallic contact plate 42 adapted to engage the fixed contacts 33 and 36. The contact plate 42 is insulated from the rivet 41 by insulation which includes in this instance strip 43, a washer 44, and a strip 45. Strip 43 is between 40 and 42. Washer 44 surrounds the rivet 41, and strip 45 extends along that face of the swinging leaf which is rearwardly disposed with reference to the contact plate 42. Contact plate 42, being insulated from the body of the contact leaf, is adapted to act as a bridge between the fixed contact members.

The aperture 41^a in the contact leaf is shown as a small round aperture. The hook of the spring is formed on an arc and extends through this aperture, and the spring being under tension, the hook portion is strongly held against the lower margin of the aperture 41^a. This lower margin has the special form shown more particularly in Fig. 8A, the same being beveled, as indicated at 46, to provide a cross section in the shape of an inverted V, the apex of which is indicated at 47, said apex providing a line contact with the hook of the spring, for a purpose hereinafter mentioned.

The leaf 23 has a knife-edge mounting at its lower part, which in this case is provided by engagement of the leaf with the frame member 22. The leaf is beveled at its lower edge to provide a knife edge making contact with the body of member 22 at opposite sides of the aperture 25, as indicated at 48.

The lower end of the spring 26 is mounted with respect to the actuating plate 28 in the following manner:

The lower part of the helical coil of the spring 26 is extended into a round sleeve 49, and below the lowermost turn of the coil the spring is formed to provide an integral generally round hook portion 50, which is removably connected to the sleeve 49 by means of a crosspin 51. The hook 50 engages the crosspin 51 at the lower surface of the latter in a region intermediate the ends of the crosspin. The ends of the crosspin are received in diametrically opposite portions of a rabbet 52 provided in sleeve 49, this portion of the sleeve being below the actuating plate 28, and that portion of the sleeve engaging the lowermost turn of the coil being above the actuating plate. In the form shown, the sleeve 49 has a body portion of an internal diameter approxi-

mately equal to the external diameter of the spring coil, said body portion being received in a round hole 53 in plate 28. Immediately below the plate 28 the sleeve is enlarged to provide a flanged head 54 in which the rabbet 52 is formed, the flanged head engaging the lower surface of plate 28.

The spring 26 being under tension when the switch is completely assembled, the swinging leaf 23 is strongly held in its pivot notches or recesses, and the actuating plate, through the action of the flanged sleeve 49, held in an upper position in which it can be swung while in engagement with the spacing and pivoting elements 29 and 30. Both of these elements have lower knife-edge portions 29' and 30', respectively, engaged in notches or recesses of the actuating plate, and they both have upper knife-edge portions 29'' and 30'', respectively, engaging notches in the member 22. The manipulating extension 31, previously mentioned, is formed on member 30 intermediate of the two upper knife-edge portions which are provided on said member.

In Fig. 3 the switch is illustrated as being in the "off" position, the swinging contact leaf being tipped somewhat to the left of a vertical transverse plane passing through its lower edge. To close the switch, the extension 31 is grasped and swung to the left, as indicated by the dotted lines. This causes the actuating member 28 to be moved to the right, carrying with it the lower part of the spring and causing the upper end of the spring to pull the upper part of the leaf to the right so that it comes against and is held against the fixed contacts 33 and 36. This position will then be held until there is a reverse movement of the extension.

In the "off" position of Fig. 3 the lower extremity of the spring and the contact line 47, previously mentioned, are located to the left of the pivot point of the leaf, thereby holding the leaf firmly in the "off" position. In moving the spring from the full-line position of Fig. 3 to the dotted-line position, the lower extremity of the spring and its upper contact line bearing against the contact line 47 of the leaf are brought to the right of the pivot point of the leaf, and when this occurs the leaf snaps quickly to the "on" position.

It is noted that in moving the lower part of the spring and sleeve 49, moving with the actuating member, engages the body of the spring, in other words, a portion of its coil, the region of such engagement being, therefore, intermediate of the ends of the spring, and this engagement, therefore, causing a positive movement of the spring in this region. This has a very beneficial effect in bringing about a rapid and effective snapping action of the leaf between its two positions. It is also to be noted that the line of engagement between the spring and the swinging leaf is quite close to the pivot point of the leaf, there being a sharp line of engagement, as above described. The distance from the lower edge of the leaf to its metallic upper edge is preferably short in comparison to the length of the spring, as illustrated in the drawings.

In the modified form shown in Figs. 9 to 13, inclusive, the manual manipulation is somewhat different from that described above, inasmuch as the lower swinging member is actuated directly, being grasped by the fingers and moved in one or the other direction. In this particular form the actuating plate connected to the spring is combined with an elongated member of insu-

lating material adapted to be grasped by the fingers.

In this second form the upper insulation block 55 has the cut-away portion 56 in which the swinging leaf 57 operates to bridge two fixed contacts 58 and 59, respectively, located within the cut-away portion. These contacts 58 and 59 are connected to conductor strips 60 and 61, which in this instance are set edgewise in the block, as shown in Fig. 13. At their outer ends these conductor strips extend out of the block at the sides of an extension 62 on the block, and in these regions the conductor strips are equipped with threaded sockets for terminal screws screwing into the extension 62. The contacts 58 and 59 are pieces of metal suitably attached to the respective conductor strips and located at opposite sides of a separating fin 63 of insulating material provided in connection with the insulating block.

The swinging leaf 57 is generally similar to that previously described, but different in some features. It comprises a metal member 64 engaging spring 65a in the manner previously described, and pivoted in the manner previously described. Riveted to this metal member is a small plate 65 of insulating material. Mounted upon the part 65 is a metallic bridge member 66 in the form of a plate having a rocking mounting intermediate of its ends, so that it can tilt in a horizontal plane with reference to Fig. 9 and can adapt itself to the lie of the contact members which it bridges. In the particular case shown, the member 66 has intermediate of its ends a small integral projection bearing against the opposed face of the insulating plate 65. A rivet member 67 having a flat shank passes with clearance through holes formed in the parts 65 and 66, and this member has heads which secure the parts together in a manner to allow the member 66 to have the tilting or tipping movement previously mentioned. The connecting member is elongated in an upward direction with reference to Fig. 11, and it will be noted that the members 65 and 66 have portions disposed above the upper edge of member 64. It will also be noted that the upper edge portion of the swinging leaf is provided with a notch 68 whereby the adjacent end of the rivet member 67 is exposed, and this end of the rivet member may, when the switch is opened, come against the inner end of a stop screw 69 threaded in the insulating block and adapted to be held in the adjusted position by a clamping nut 70. The particular function of screw 69 will be mentioned hereinafter.

In this form the knife-edge spacing plates are shown at 71, the same being engaged, as before, with the U-shaped metal frame member, which is here indicated at 72. At their lower edges these plates engage the plate 73, which corresponds to the plate 28, previously described. In this case, however, the plate 73 has integral therewith the member in which the lower end of the spring 65a is engaged and secured, said member being indicated at 74. Member 74 provides a round, upwardly directed wall portion integral with plate 73, which is rabbeted interiorly to receive the lowermost turn of the spring. The plate 73 is fastened by screws 75 to an elongated block-like member 76 of insulating material. This member and the plate 73 have meeting faces, portions of which provide an annular recess in which is located the pin 77 which engages the lower hook portion 78 of the spring. There is also provided, as shown in Fig. 9, a round recess

in block 76 in which the lower hook portion of the spring is disposed. In assembling the parts the lower end of the spring and the pin 77 are placed in position with respect to the plate 73, and the insulating block is then placed in position to enclose the pin, and the screws are inserted for attaching the insulation block to the metal plate.

In this form the longitudinal movement of the composite actuating member 73, 76 is controlled by an adjustable stop member carried by the frame 72 adapted to engage one of the spacer members 71, in this case the right-hand member (Fig. 9). Here a stop screw 79 is carried by the leg of the metal frame, and is locked in longitudinally adjusted position by nuts 80 and 81, and the screw has an inner extremity adapted to be engaged by the adjacent spacer plate. By adjusting this screw, the length of the movement or stroke of the actuating member may be adjusted. In this case the screw limits movement of the actuating member toward the right (Fig. 9), whereas the adjustable screw 69, previously mentioned, limits swinging movement of the contact member toward the left.

In the switch shown in Figs. 9 and 10, the switch is adjustable to be self-closing. In opening the switch the same will not be moved to the position shown in Fig. 10, as the screw 69 will not permit sufficient movement of the swinging contact leaf to bring the leaf to a position where it will remain disengaged. However, by adjusting the screw 69 it is possible to have the leaf moved to the fully opened position, where it will remain open as in Fig. 10.

In this form, clearance is provided between the frame 72 and the plate 73 by notching the lower extremities of the depending portions of the frame. In the form first described the depending portions or legs of the frame act as stops for the actuating plate.

The third form of the device, shown in Figs. 13A and 14, is one in which the switch can be biased to one position and movable to the other position by the action of a thermostatic element such as a thermostatic bellows. More specifically, the switch is normally closed, but is adapted to be opened by the thermostat when a predetermined high temperature is reached. In general, this form is similar to those previously described, the same comprising an insulation block 82, a metal frame 83, a swinging leaf 84, a coil spring 85, and an actuating plate 86 provided with connections to the spring which are similar to those in the form first described. The swinging leaf cooperates with contact members 87, 88, which in this instance are carried by conductive arms secured to and extending laterally outwardly from block 82 in the manner shown in Figs. 13A and 14. Associated with the attached ends of the conductive arms are terminal screws, as shown, to which the electric wires are adapted to be fastened. The switch is adapted to be fastened in a suitable location by means of an attaching plate 89. This attaching plate is secured to the insulation block 82 by integral arms 90, which extend at right angles to the body of the plate. The thermostatic element is illustrated as a bellows 91 fastened to a fixed part by a member 92 at one end of the bellows, the other bellows end, which is the movable end, being connected to a member 93 in the nature of a slide, which is attached to one end of a lever 94. The switch is arranged so that the actuating plate 86 is adapted to have a vertical movement, and the lever 94 has an end 95 extending under

a lip 96 on frame 83. The lever 94 bears intermediate of its ends against the upper edge of the plate 86, and when the bellows is expanded to a certain degree by the heat of the surrounding atmosphere, the bellows causes downward movement of plate 86, which is effective to throw the switch to the "off" position and hold it "off" until a certain amount of cooling has taken place.

In this case the swinging leaf has a metallic part, as in the two forms previously described, and this part is riveted to a part 97 of insulating material extended out of the insulation block so as to be in proximity to the cooperating contact members. The part 97, in turn, carries a metallic bridge member 98 which is similar to that of the second form, having a similar tiltable mounting. The swinging contact can be held by a screw 99 against opening movement past the dead center.

It will be seen that in the particular forms herein described the switch comprises a composite device having interconnected elements, one of which is an insulating block having a cut-away portion for a swinging leaf, the other element being a frame element to which the leaf is pivoted by a knife-edge arrangement, the block being equipped with terminals having contacts adapted for bridging, the leaf having a member for bridging the contacts. The metallic frame member serves as a mounting for an actuating member swingingly mounted with reference to the frame member by spacing knife-edge elements interposed between the frame member and the actuating member, there being a helical spring for imparting a snap action to the switch, which spring is located between the aforesaid spacing elements and is hooked into the swinging leaf at one end of the spring and into the actuating member at the opposite end of the spring. The spring, as so connected into the switch structure, holds the principal parts in the assembled relation, thus eliminating various parts in the nature of screws, bolts and the like, which have been used heretofore. Moreover, the principal parts of the switch can be of reduced size and greater compactness, and, more important, the snap action which is imparted to the switch in its operation is extremely rapid, and more effective than previous structures in eliminating arcing and pitting.

While the actuating member is a swinging member, it at all times maintains its general parallelism to the frame, owing to the provision of the spacing members or leaves at opposite sides of the spring. As the spacing leaves, as well as the contact leaf, swing on knife edges, movement of the switch can be effected with a minimum of friction.

The knife-edge pivoting arrangement herein described eliminates the need of long travel hitherto required in connection with a toggle member, and permits making or breaking of a contact on a movement as small as $\frac{1}{64}$ th of an inch. Moreover, the switch may be set to keep the circuit normally open or normally closed, which is a feature not obtainable with toggles. This is accomplished with knife-edge pivots serving as bearings, which, for all practical purposes, are frictionless, eliminating the necessity of lubrication, eliminating high-pressure resistance at dead center, and insuring long life.

While some modifications are shown herein, various other modifications may be made, and other changes adopted within the broad prin-

ciples of the invention and the scope of the claims.

What I claim is:

1. A manually operable electric switch comprising an insulation block and a metal frame applied to the block at one face of the latter, the intermediate portion of the block being cut away to provide operating space for a contact leaf, and the block being provided with terminals and with contact members at one side of the cut-away portion, the frame being cut away substantially in line with the cut-away portion of the block, a metal leaf in said cut-away portion of the block carrying a contact strip insulated from the leaf for bridging said contact members and having knife-edge pivoting engagement with said frame, a coil spring connected to said leaf adjacent its pivot, an elongated actuating member to which said spring is connected at the opposite end thereof intermediate of the ends of the actuating member, and means spacing and pivotally mounting said actuating member from said frame so that it has a swinging movement.
2. A manually operable electric switch comprising an insulation block and a metal frame applied to the block at one face of the latter, the intermediate portion of the block being cut away to provide operating space for a contact leaf, and the block being provided with terminals and with contact members at one side of the cut-away portion, the frame being cut away substantially in line with the cut-away portion of the block, a metal leaf in said cut-away portion of the block carrying a contact strip insulated from the leaf for bridging said contact members and having knife-edge pivoting engagement with said frame, a coil spring connected to said leaf adjacent its pivot, an elongated actuating member to which said spring is connected at the opposite end thereof intermediate of the ends of the actuating member, and means spacing and pivotally mounting said actuating member from said frame so that it has a swinging movement.
3. A manually operable electric switch comprising an insulation block and a metal frame applied to the block at one face of the latter, the intermediate portion of the block being cut away to provide operating space for a contact leaf, and the block being provided with terminals and with contact members at one side of the cut-away portion, the frame being cut away substantially in line with the cut-away portion of the block, a metal leaf in said cut-away portion of the block carrying a contact strip insulated from the leaf for bridging said contact members and having knife-edge pivoting engagement with said frame, a coil spring connected to said leaf adjacent its pivot, an elongated actuating member to which said spring is connected at the opposite end thereof intermediate of the ends of the actuating member, and knife-edge leaf elements interposed between the actuating member and the frame, said actuating member having a swinging movement.
4. A manually operable electric switch comprising an insulation block and a metal frame applied to the block at one face of the latter, the intermediate portion of the block being cut away to provide operating space for a contact leaf, and the block being provided with terminals and with contact members at one side of the cut-away portion, the frame being cut away substantially in line with the cut-away portion of the block, a metal leaf in said cut-away portion of the block carrying a contact strip insulated from the leaf for bridging said contact members and having knife-edge pivoting engagement with said frame, a coil spring connected to said leaf adjacent its pivot, an elongated actuating member to which said spring is connected at the opposite end thereof intermediate of the ends of the actuating member, and means pivoting said actuating member from said frame so that it has a swinging movement, said spring by being connected to the contact leaf and actuating member maintaining the actuating member in the assembled position, the contact leaf having a snap action imparted to it through the swinging movement of the actuating member, and the actuating member having means of connection between it and the body of the coil serving to shift the coil laterally.
5. In an electric switch, the combination of a frame member having a plate portion cut away

intermediate of its ends to provide an opening, a contact leaf having knife-edge engagement with said plate portion adjacent said opening, said leaf having an aperture adjacent its pivot, a coil spring having at one end hooking engagement with the apertured portion of said leaf at one side of said plate portion and extending to the other side of said plate portion, parallel knife-edge elements at the last-named side of the plate portion engaging the plate portion, an actuating member spaced from said plate portion by said elements and movable parallel to said plate portion, and means of connection between said actuating member and the other end of said spring.

5. In an electric switch, the combination of a frame member having a plate portion cut away intermediate of its ends to provide an opening, a contact leaf having knife-edge engagement with said plate portion adjacent said opening, said leaf having an aperture adjacent its pivot, a coil spring having at one end hooking engagement with the apertured portion of said leaf at one side of said plate portion and extending to the other side of said plate portion, knife-edge elements at the last-named side of the plate portion engaging the plate portion at respective points in the length of said portion, an actuating member spaced from said plate portion by said elements, and means of connection between said actuating member and the other end of said spring including a sleeve member in which said spring is engaged.

6. In an electric switch, the combination of a frame member having a plate portion cut away intermediate of its ends to provide an opening, a contact leaf having knife-edge engagement with said plate portion adjacent said opening, said leaf having an aperture adjacent its pivot, a coil spring having at one end hooking engagement with the apertured portion of said leaf at one side of said plate portion and extending to the other side of said plate portion, knife-edge elements at the last-named side of the plate portion engaging the plate portion, an actuating member spaced from said plate portion by said elements, and means of connection between said actuating member and the other end of said spring including a sleeve member in which said spring is engaged, said actuating member being maintained in its assembled relationship to the switch structure by its connection to said spring, and said connection being a detachable connection.

7. In an electric switch, the combination of a frame member having a plate portion cut away intermediate of its ends to provide an opening, a contact leaf having knife-edge pivot engagement with said plate portion adjacent said opening, said leaf having an aperture adjacent its pivot, a coil spring having at one end hooking engagement with the apertured portion of said leaf at one side of said plate portion and extending to the other side of said plate portion, an actuating member at the last-named side of said plate portion to which the other end of said spring is hooked, and pivoting knife-edge spacing elements between said actuating member and said plate portion at opposite sides of the spring held in position by the connection of the spring to said leaf and said actuating member, said spacing elements mounting said actuating member so that it has a swinging movement but in its movement remains generally parallel to said plate portion.

8. In an electric switch, the combination of a frame member having a plate portion cut away intermediate of its ends to provide an opening, a contact leaf having knife-edge pivot engagement with said plate portion adjacent said opening, said leaf having an aperture adjacent its pivot, a coil spring having at one end hooking engagement with the apertured portion of said leaf at one side of said plate portion and extending to the other side of said plate portion, an actuating member at the last-named side of said plate portion to which the other end of said spring is hooked, and pivoting knife-edge spacing elements between said actuating member and said plate portion at opposite sides of the spring held in position by the connection of the spring to said leaf and said actuating member, said spacing elements mounting said actuating member so that it has a swinging movement but in its movement remains generally parallel to said plate portion to which the other end of said spring is hooked, and pivoting knife-edge spacing elements between said actuating member and said plate portion at opposite sides of the spring held in position by the connection of the spring to said leaf and said actuating member, said spacing elements mounting said actuating member so that it has a swinging movement but in its movement remains generally parallel to said plate portion, the apertured portion of said contact leaf having a margin which is V-shaped in cross section and has its apex in contact with the hooked portion of the spring.

25. 9. An electric switch for quick-break and quick-make of current, comprising two members one of which engages the other by interposed V-shaped pivot spacers for parallel longitudinal movement of one member while the other member is stationary, a fly-leaf contactor having a V-shaped pivot engaged with the stationary member, and a spring connected to the fly-leaf contactor and to the movable member providing a snap action of the contactor by longitudinal motion of the movable member, said spring holding all of said parts in the assembled position.

30. 10. An electric switch for quick-break and quick-make of current, comprising two members one of which engages the other by interposed V-shaped pivot spacers for parallel longitudinal movement of one member while the other member is stationary, a fly-leaf contactor having a V-shaped pivot engaged with the stationary member, and a spring connected at one end to the fly-leaf contactor and at the other end to said movable member providing a snap action of the contactor by longitudinal motion of said movable member, said spring having a body in the form of a coil which is engaged with said movable member.

35. 11. An electric switch comprising an elongated insulation block provided with interconnected terminals and contact members, the block having a portion thereof cut away adjacent the contact members to provide operating space for a contact leaf for bridging said contact members, a frame applied to one face of the block and having a cut-away portion substantially in line with the cut-away portion of the block, a bridging contact leaf in said cut-away portion of the block having knife-edge pivoting engagement with said frame on the face of the frame applied to the block, a coil spring connected at one end to the contact leaf adjacent its pivot point and extending through the cut-away portion of the frame, an elongated actuating member connected to the other end of the spring intermediate of the ends of the actuating member and having a portion engaging the body of the spring, pivoting knife-edge spacing elements interposed between said actuating member and said frame for pivotally mounting the actuating member so that it will swing in an arc generally lengthwise 40 of said block, and manual manipulating means

for the switch comprising an extension on one of said spacing elements extending through in-line apertures in said frame and in said block.

12. A manually operable electric switch comprising an elongated insulation block provided with interconnected terminals and contact members, the block having a portion thereof cut away adjacent the contact members to provide operating space for a contact leaf for bridging said contact members, a frame applied to one face of the block and having outstanding legs, said frame having a cut-away portion substantially in line with the cut-away portion of said block, a bridging contact leaf in the cut-away portion of the block having knife-edge pivoting engagement with the frame on the face of the frame applied to the block, a coil spring connected at one end to the contact leaf adjacent its pivot point and extending through the cut-away portion of the frame, an elongated actuating member connected to the other end of the spring intermediate the ends of the actuating member and having a portion engaging the body of the spring, pivoting knife-edge spacing elements interposed between said actuating member and said frame for pivotally mounting said actuating member so that it will swing in an arc generally lengthwise of said block, adjustable stop means carried by one of said frame legs for inhibiting the pivotal movement of the actuating member through the engagement of the stop means with one of said pivoting spacing members, and adjustable stop means for the contact leaf carried by said block for inhibiting the swing of the contact leaf and permitting the contact leaf to be biased toward the contact members thereby permitting a self throw in this direction through the action of said spring.

13. A manually operable electric switch comprising an elongated insulation block provided with interconnected terminals and outstanding contact members on one face thereof, the block having an opening in it at one side of the contact members, a frame applied to the opposite face of the block and having a cut-away portion substantially in line with the opening in the block, a bridging contact leaf extending into the opening of the block for bridging the contact members and having knife-edge pivoting engagement with the frame on its face applied to the block, a spring having one of its ends connected to the contact leaf adjacent its pivot and having its other end extending through the cut-away portion of the frame, an elongated actuating member connected to the other end of the spring intermediate of the ends of the actuating member, and pivoted spacer elements interposed between the frame and the actuating member for pivotally mounting the latter so that it will swing in an arc generally lengthwise of the block.

14. An electric switch for quick-break and quick-make of current comprising two elongated

substantially parallel members one of which is movable while the other is stationary, said stationary member having an interconnected contact and terminal and having a cut away portion, a fly leaf contactor cooperating with said contact and having a V-shaped pivot engaged with the stationary member and having an aperture adjacent said pivot, said aperture in the contactor having the lower margin thereof beveled to provide a cross section in the shape of an inverted V and the apex providing a line contact for a hooked end of a coil spring, and a tensioned coil spring having one end formed in the shape of a hook engaging said line contact of the contactor, said spring extending through said cut away portion of the stationary member and having its other end fastened to the movable member, said movable member having a portion thereof engaging the body of said spring to move the spring laterally when the last-mentioned member is moved longitudinally thereby imparting a snap action to said fly leaf contactor.

15. An electric switch for quick-break and quick-make of current comprising two elongated substantially parallel members, means for pivoting one member to the other for swinging movement of one member while the other is stationary, said stationary member having an interconnected contact and terminal and having a cut away portion, a fly leaf contactor cooperating with said contact and having a V-shaped pivot engaged with the stationary member and having an aperture adjacent said pivot, said aperture in the contactor having the lower margin thereof beveled to provide a cross section in the shape of an inverted V and the apex providing a line contact for a hooked end of a coil spring, and a tensioned coil spring having one end formed in the shape of a hook engaging said line contact of the contactor, said spring extending through said cut away portion of the stationary member and having its other end fastened to the swingable member, said swingable member having a portion thereof engaging the body of said spring to move the spring laterally when the last-mentioned member is swung longitudinally thereby imparting a snap action to said fly leaf contactor.

TOMUN FINIZIE.
